(57) **CLAIM**

The ornamental design for a lid, as shown and described.

DESCRIPTION

FIG. 1 is an elevated perspective view of a lid according to my new design, shown in a closed configuration;

FIG. 2 is a top plan view thereof;

FIG. 3 is a side perspective view thereof;

FIG. 4 is a left side view thereof;

FIG. 5 is a front view thereof, the rear view being a mirror image of the front view;

FIG. 6 is a right side view thereof;

FIG. 7 is a bottom perspective view thereof;

FIG. 8 is another elevated perspective view of a lid according to my new design, shown in an open configuration;

FIG. 9 is another elevated perspective view thereof;

FIG. 10 is a left side view thereof;

FIG. 11 is a front view thereof, the rear view being a mirror image of the front view;

FIG. 12 is a right side view thereof;

FIG. 13 is a bottom perspective view thereof;

FIG. 14 is a bottom plan view thereof; and,

FIG. 15 is another bottom perspective view thereof.

The broken lines in the figures depict portions of the lid that form no part of the claimed design.

1 Claim, 15 Drawing Sheets
